REFRIGERATOR LATCH

Arthur C. Shuart, Evansville, Ind., assignor to
 Servel, Inc., New York, N. Y., a corporation of
 Delaware

Application March 14, 1945, Serial No. 582,732

10 Claims. (Cl. 292—255)

1

My invention relates to a household refrigerator having a treadle-operated door latch.

The door of a household refrigerator should be easily opened and closed to afford satisfaction in the daily use of the refrigerator. Accordingly, it is usual to provide a latch mechanism which requires application of a force to unlatch the door, but which automatically latches when the door is swung closed. A refrigerator door presents a special latching problem in that the door must be sealed when it is closed to minimize heat leaking into the refrigerator. This sealing is usually afforded by a gasket which is compressed between the periphery of the door and the door jamb when the door is closed. No matter how light and flexible the gasket, considerable force is required to evenly compress it. This gasket-compressing force has to be supplied by the latch in the case of a self-latching door. The latch has to get from somewhere the necessary energy to produce such force and, of course, gets it from the user who stores the energy in the latch when he cocks the latch to unlatch the door. Either that, or the user has to supply the force when he closes the door.

It is known to provide a pedal for unlatching a refrigerator door to permit the use of both hands for carrying things to be put in the refrigerator. Heretofore, either the pedal stuck out at one place in front of the refrigerator or it was beneath a refrigerator elevated on legs. In either case, one had to approach the door at one spot and, particularly at night or with an armload, feel around with a foot for the pedal.

It has been proposed to provide such a door-opening pedal on the more modern refrigerator which is enclosed to the floor, the pedal being located in a toe space beneath the bottom or apparatus compartment door. This merely aggravates the pedal searching by foot. Moreover, the linkage between the pedal and latch has to be massive to transmit the latch-cocking force, and requires heavy foot pressure because the force is greatly decreased in transmission in order to get distance of movement.

I have invented a self-latching refrigerator having a treadle door opener that does not stick out appreciably in front of the refrigerator. It does not require the foot to be lifted completely off the floor. It is available no matter from what direction the door is approached. The toe is guided naturally on to the treadle and the latter is shaped to naturally convert a large vertical component foot pressure applied in any fashion. This full force component is transmitted un-

2

diminished to cock the latch by a pulling mechanism which permits the use of very light material. The treadle is counter-balanced and pivoted at a point far behind the front of the refrigerator giving the tread portion nearly straight line movement and smooth, quiet action. Further, the tread appears as a decorative portion of the refrigerator base rather than an isolated appendage.

10 The above and other objects and advantages of the invention are attained as set forth in the detailed specification taken with the drawings, in which:

Fig. 1 is a perspective view of a refrigerator cabinet illustrating one embodiment of my invention;

Fig. 2 is a rear elevational view of the cabinet closure members, partly in section and taken substantially on lines 2—2 of Figs. 3 and 4, looking in the direction of the arrows;

Fig. 3 is a vertical sectional view taken on line 3—3 of Fig. 4;

Fig. 4 is a horizontal sectional view through the base of the cabinet showing the treadle supporting platform and attached treadle in the top plan view;

Fig. 5 is a vertical sectional view taken on line 5—5 of Fig. 4;

Fig. 6 is a vertical sectional view taken on line 6—6 of Fig. 4;

Fig. 7 is a horizontal sectional view through the door latch taken substantially on line 7—7 of Fig. 2, looking in the direction of the arrows; and

Fig. 8 is a horizontal sectional view similar to Fig. 7, but showing the cabinet door in unlatched position.

Referring now to the drawings, 10 designates generally a domestic refrigerator cabinet provided with a hinged door 11 for gaining access to a food storage compartment 10a, a closure member 12 for an apparatus compartment 10b and a supporting base 13. Door 11 is provided with a latch mechanism 14 (Figs. 7 and 8) to be described in detail hereinafter. A treadle 15 is positioned in front of base member 13 and traverses the entire front of the cabinet beneath closure member 12. As shown in Figs. 3 and 4, treadle 15 is rigidly connected to a pivoted platform 16 by means of a pair of brackets 17. Platform 16, which is located within the base of the refrigerator cabinet, includes four channel members 16a, 16b, 16c and 16d, with portions thereof arranged in back-to-back relation, and a pair of gusset plates 16e and 16f. The channel members

50

and the gusset plates are secured into a rigid structure as by spot welding or otherwise. Platform 16 is rigidly secured, as by welding, to a shaft 18 which, in turn, is rotatably supported at its two ends by a pair of brackets 19. As shown, the brackets 19 are mounted on the rear portion of the supporting base. Treadle 15 is provided with a decorative corrugated tread 20 formed of stainless steel or other suitable polished material and inclined upwardly from the front edge thereof at an angle of approximately thirty degrees with the horizontal. A pair of brackets 13b provided with rubber cushions 13c are attached to the front of base channel member 13a for limiting downward movement of the treadle. A tension spring 16g is attached at one end to channel member 13a and at its opposite end to gusset plate 16f for counter-balancing the treadle.

Treadle 15 is connected to latch mechanism 14 by means of a rod 21, a lower hook member 22, an upper hook member 23, a flexible vertical cable 24, a bell crank 25 and a flexible horizontal cable 26. Bell crank 25 may be replaced by a pulley (not shown) in which case a single flexible cable which passes over the pulley is used to connect hook member 23 to latch mechanism 14. As shown in Figs. 2 and 3, the lower end of rod 21 is connected to treadle 15 by means of a pin 27 which is journaled in a U-shaped bracket 28 which, in turn, is welded or otherwise secured to the under-surface 15a of the treadle. The upper end of rod 21 is flattened and provided with a serrated face 21a adapted to mesh with a flattened and serrated lower portion 22a of hook member 22. The upper flat portion of rod 21 is provided with a pair of circular openings and the lower flat portion of hook member 22 is provided with a pair of elongate openings through which pass a pair of bolts 29; the arrangement being such that the combined length of rod 21 and hook member 22 may be adjusted. Hook member 22 is square in cross-section and is guided in a square opening in a bracket 30 which, in turn, is welded or otherwise secured to the refrigerator cabinet. A leaf spring 31, supported by bracket 30, yieldably holds rod 21 and hook member 22 in proper position relative to upper hook member 23.

As shown, the lower right corner of door 11, as viewed in Fig. 1, is provided with a housing member 32 adapted to form a recess to receive the upper and lower portions respectively of hook members 22 and 23. Hook member 23 is square in cross-section and is guided in a sleeve 33 having a square passage formed therein. Sleeve 33, which is screw-threaded at its lower end, projects through an opening in housing member 32 and is secured to the housing by means of a nut 34. Hook member 23 is drilled to receive a horizontal pin 23a which contacts nut 34 for limiting upward movement of the hook member. The upper end of hook member 23 is screw-threaded to receive an elongate nut 35. A lock nut 36 is provided for locking nut 35 on hook member 23. Nut 35 is formed with a socket (not shown) to receive a ball (not shown) formed on the lower end of cable 24. The upper end of cable 24 is formed with a ball 24a received in a socket 31a formed in a stirrup or connecting member 31 for connecting cable 24 to bell crank 25. Stirrup 31 is formed with a lateral slot (not shown) whereby the cable may be threaded into the stirrup.

Bell crank 25 is pivotally supported on a bracket 38 by a pivot pin 39. Bracket 38 is

welded or otherwise secured to a channel cross brace 40. Pivot pin 39 is provided with a torsion spring 41 having one end, 41a, attached to bell crank 25 and the opposite end, 41b, attached to bracket 38; the arrangement being such that bell crank 25 is biased for clockwise rotation which, in turn, tensions cable 24. Horizontal cable 26 is connected at one end to bell crank 25 by a stirrup 42 which is generally similar to stirrup 37. At its opposite end, cable 26 is connected to latch mechanism 14 by a stirrup 43. Stirrup 43 is formed with an L-shaped slot 43a and with a socket 43b; the arrangement is such that a ball 26a formed on the end of cable 26 is threaded through the slot and received by the socket.

Referring now to Figs. 2, 7 and 8 of the drawings, latch mechanism 14 includes a housing member 44 formed of two parallel sides 44a and 44b connected by an integral bridge member 44c. Bridge member 44c is provided with a rubber cushion 44d. Housing 44 is formed with two oppositely-projecting flanges 45 and 46 arranged in parallel relation with a flanged portion 11a of door 11 and connected to said flanged portion by machine screws (not shown). The opposite end of housing 44 is secured to cross brace 40 by means of a pair of bolts 47. A latch bolt 48 formed with two parallel side members 48a and 48b (side 48b not shown) connected by an integral bridge member 48c is slidably mounted in a bolt guide 49. Bolt guide 49 is formed of a channel member which fits between and is welded to the sides 44a and 44b of housing 44. Latch bolt 48 is pivotally connected at one end to stirrup 43 by a pivot pin 50 which, in turn, is mounted on a yoke 51. The opposite end of latch bolt 48 is provided with a roller 52 journaled on a pin 53 secured between the two sides of said bolt.

Yoke 51 is formed of two parallel sides 51a and 51b (side 51b not shown) connected by an integral bridge member 51c and pivotally mounted between the sides of housing 44 by a pivot pin 54 secured to the housing. A pivot pin 55 is secured between the parallel sides of yoke 51 and is adapted to pivotally support one end of a spring guide 56. The opposite end of guide 56 is provided with a pair of opposed slots 56a (only one of which is shown) to receive a lug 57 formed on bolt guide 49. A compression spring 58 is positioned on spring guide 56 and is held under compression by bolt guide 49 and pivot pin 55. As shown in Fig. 7, the arrangement of slots 56a and of lug 57 is such that limited movement is provided between spring guide 56 and bolt guide 49.

A lever or trigger 60 straddles yoke 51 and is pivotally mounted between the sides of housing 44 by a pivot pin 61. Trigger 60 is formed of two parallel sides 60a and 60b (side 60b not shown) connected by an integral bridge member 60c. Bridge member 60c is provided with a projecting lug or trip member 60d. A torsion spring 62 coiled about pivot pin 61 and having one end, 62a, in contact with bridge member 60c and its opposite end, 62b, in contact with an inner flange 49a of bolt guide 49 biases trigger 60 for clockwise rotation. Each of the sides 60a and 60b of trigger 60 is formed with a cam surface 60e adapted to contact and ride over opposed cam surfaces 51e (only one of which is shown) formed on outwardly-projecting bosses 51f on each of the side members 51a and 51b of yoke 51. As shown in Figs. 7 and 8, inner panel 11b of door 11 is provided with an opening 11c to receive a striker or latch keeper 64 when the door ap-

proaches closed position. Latch keeper 64 is mounted in any suitable manner on a bracket 65 which, in turn, is welded or otherwise secured to the flanged portion 10c of the refrigerator cabinet. A gasket 66 attached to inner panel 11b provides a seal between the cabinet and door when the door is in closed position.

In operation, when it is desired to open the door to the food compartment, the operator depresses the treadle by engaging any portion of the tread 20 with his toe, and even though pressure is applied inward as well as downward, the construction and arrangement of the tread and the long pivot arm of the treadle is such that the pressure is substantially all resolved into a downward vertical component. This causes the treadle to descend against the action of spring 16g; downward movement of the treadle being limited by contact with cushions 13c. As the treadle is depressed, rod 21 and attached hook 22 are pulled vertically downward, causing hook 23 and cable 24 to be pulled vertically downward. This causes bell crank 25 to be rotated in a counter-clockwise direction, as viewed in Fig. 1, pulling horizontal cable 26 and attached stirrup 43 to the left. In this manner, bolt 48 is pulled to the right, as view in Figs. 7 and 8, and yoke 51 is rotated in a clockwise direction about pivot pin 54 from the position shown in Fig. 7 to that shown in Fig. 8. As yoke 51 is rotated, spring 58 is compressed between bolt guide 49 and pivot pin 55 and cams 51e are moved from in front of cams 60e with the result that torsion spring 62 causes trigger 60 to rotate in a clockwise direction from the position shown in Fig. 7 to that shown in Fig. 8, whereby cams 51e and 60e cooperate to lock yoke 51 in the cocked position shown in Fig. 8 and energy is stored in compressed spring 58. Also, as trigger 60 is rotated by spring 62, the roller 52 of latch bolt 48 having been drawn clear of latch keeper 64, projection 60d of the trigger bears against the latch keeper and springs the door to partly open position. From this partly open position, the door is swung to fully open position by the person wishing to gain access to the food storage compartment by shoving the door with his elbow or body. If desired, additional springs or other resilient means (not shown) may be provided for springing the door to partly open position once the latch has been released.

When it is desired to close door 11, the door is swung to closed position whereby latch keeper 64 engages and moves projection 60d of trigger 60. This causes the trigger to be rotated in a counter-clockwise direction against the resistance of torsion spring 62, during which rotation the lock formed by cams 51e and 60e is tripped, yoke 51 is rotated in a counter-clockwise direction by the expansion of compressed spring 58 and bolt 48 is driven home. The energy stored in compressed spring 58 is such that as the bolt is driven home, roller 52 contacts the inclined face 64a of latch 64 and the door is wedged into firm sealing engagement with the cabinet, as is shown by the compression of sealing gasket 66. Any shock that may be produced by the tripping of yoke 51 is absorbed by the rubber cushion 44d in housing member 44c.

While I have illustrated and described a particular embodiment of my invention, it obviously may take other forms and be variously applied within the scope of the following claims.

What is claimed is:

1. Latch mechanism for a hinged door of a

- cabinet including a latch bolt secured to said door, a treadle mounted on said cabinet and having a tread traversing substantially the entire front of said cabinet below said door, means operatively connecting said treadle to said latch bolt, said means including a vertical element operatively connected to said treadle and passing upwardly through said door on the hinged side thereof, and a horizontal element connected at one end to said vertical element and at its opposite end to said latch bolt.
2. A latch mechanism for a hinged door of a refrigerator cabinet including a latch bolt, a foot treadle disposed at the lower portion of said cabinet and having a tread that traverses substantially the entire front of said cabinet below said door, a rigid platform pivotally mounted in the lower portion of said cabinet at two sides thereof, means rigidly connecting said foot treadle to said platform, and means operatively connecting said foot treadle to said latch bolt.
3. In a latch mechanism for a door of a refrigerator cabinet, a treadle positioned across the front of said cabinet at the base thereof and having a length of substantially the width of said cabinet, a latch bolt mounted on said door, means operatively connecting said treadle to said latch bolt, said means including a hook connected to said treadle, a second hook normally spaced from but adapted to be actuated by said first hook, and a flexible member connected at one end to said second hook and at its opposite end to said latch bolt.
4. In a latch mechanism for a refrigerator cabinet having upper and lower compartments and a supporting base, said latch mechanism including a latch bolt, a treadle positioned across the front of said cabinet immediately in front of said supporting base and pivotally mounted on two sides of said supporting base, means counter-balancing said treadle, means connecting said treadle to said latch bolt, said last-named means including a rod operatively connected to said treadle and projecting upwardly through the closure member of said lower compartment into the closure member of said upper compartment, and means mounted in the closure member of said upper compartment operatively connected at one end to said rod and at its opposite end to said latch bolt.
5. In a latch mechanism for a refrigerator cabinet having upper and lower compartments, closure members for said compartments and a supporting base, said latch mechanism including a latch bolt, a treadle located immediately in front of said supporting base and pivotally mounted on two sides of said supporting base near the rear thereof, said treadle having a tread of substantially the same length as the width of said refrigerator cabinet, said tread being upwardly inclined from the front edge thereof, means counter-balancing said treadle, means connecting said treadle to said latch bolt, said last-named means including a rod operatively connected to said treadle and projecting upwardly through the closure member of said lower compartment into the closure member of said upper compartment, and a tension member mounted in the closure member of said upper compartment releasably connected at one end to said rod and its opposite end to said latch bolt, the construction and arrangement being such that said latch bolt is released by foot pressure on any part of said tread and the connection between said treadle and latch bolt is broken by said counter-balancing means when

7
foot pressure is removed from said tread whereby the closure member of said upper compartment is free to open.

6. A latch mechanism for a refrigerator cabinet having upper and lower compartments, closure members for said compartments and a supporting base, said latch mechanism including a latch bolt, a treadle including a rigid platform pivotally mounted to said base near the rear thereof and a tread positioned across the front of said base, means counter-balancing said treadle, means operatively connecting said treadle to said latch bolt, said last-named means including a rod operatively connected to said treadle and projecting upwardly through the closure member of said lower compartment into the closure member of said upper compartment, and a flexible member mounted in the closure member of said upper compartment releasably connected at one end to said rod and at its opposite end to said latch bolt, the construction and arrangement being such that said latch is released by foot pressure on any part of said tread and the connection between said treadle and latch is broken by said counter-balancing means when foot pressure is removed from said treadle whereby the closure member of said upper compartment is free to open.

7. In a latch mechanism for a refrigerator cabinet having a hinged door and a supporting base, said latch mechanism including, a treadle pivotally supported on said base and having a tread at the front of said base of substantially the same length as the width of said refrigerator cabinet, a spring-pressed latch bolt and a trigger therefor mounted in said door, means operatively connecting said latch bolt to said treadle, said last-named means including a slip connection, the construction and arrangement of said latch bolt, said trigger, said treadle and said slip connection being such that the application of foot pressure to any portion of the tread of said treadle unlatches said door and cocks said latch bolt; thereafter said door through said slip connection is free to be moved to fully opened position and when shoved to closed position said latch bolt is released, thereby drawing said door into firm sealing engagement with said cabinet.

8. Latch mechanism for a cabinet door includ-
